ATTORNEY

UNITED STATES PATENT OFFICE.

CHARLES C. MASON, OF PERTH AMBOY, NEW JERSEY.

SAFETY DEVICE.

1,267,682.

Specification of Letters Patent. Patented May 28, 1918.

Application filed January 26, 1917. Serial No. 144,720.

To all whom it may concern:

Be it known that I, CHARLES C. MASON, a citizen of the United States, residing at Perth Amboy, in the county of Middlesex and State of New Jersey, have invented certain new and useful Improvements in Safety Devices, of which the following is a specification.

This invention relates to improvements in safety devices for preventing accidents at street crossings.

The main object of the invention is to provide a reflector to be suitably positioned at a street crossing or crossings and so focused as to reflect objects in the street, and especially to permit a vehicle driver to see in said reflector an oncoming vehicle in the cross street before it actually comes into sight and thereby afford ample time for him to avoid it.

Another object is to so construct a device of this character that it may be easily suspended over the center of intersecting streets and be positioned high enough to clear all traffic.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:

Figure 1 represents a plan view of a device constructed in accordance with this invention,

Fig. 2 is a vertical section taken on the line 2—2 of Fig. 1, and

Fig. 3 is a detail vertical section taken on the line 3—3 of Fig. 2.

In the embodiment illustrated, a reflector especially designed for use at the intersection of streets is shown composed of a substantially rectangular frame in the form of a band 1 carried by a spider 2 having a collar 3 for connecting the device to a support, which support is preferably in the form of a shaft or post, not shown, which passes through said collar and with which the de-

vice is held in engagement by means of a set screw 4.

This spider as shown, has four arms radiating from the collar 3 and arranged at right angles to each other with their free ends bent downwardly and provided with hangers for engaging and supporting the band 1. These hangers are constructed by bending the free ends of the spider arms laterally outward as shown at 5 and then upwardly as shown at 6 to form hooklike hangers in which the lower edge of band 1 is mounted as shown clearly in Fig. 3. Securing clips 7 are carried by the spider arms 2 above the hooks and operate to engage the upper edge of the band 1 for clamping holding it in engagement with said hooks, as is shown clearly in Fig. 3. These clips are preferably detachably connected with the spider arms 2.

Depending brackets 8 are carried by the band 1, any suitable number of which may be employed, four being here shown, and which are designed to support casings 9 which carry the reflectors. The brackets 8 are arranged obliquely with their lower ends disposed inwardly and are provided with hook-shaped terminals 10 in which are mounted the mirror casings or frames 9. These casings 9 are preferably composed of sheet metal or other suitable material and are closed at their rear faces and open at their front, the opposite outer edges of which are U-shaped in cross section forming pockets to receive the upper and lower edges of the reflecting devices which are here shown in the form of mirrors 11. These pockets preferably open toward each other and the outer walls thereof are crimped as shown at 12, with their free edges turned inwardly to form retaining members for the cement 13 which is placed in said pockets for securing the mirrors rigidly in position. The closed rear wall of the casing is offset outwardly from the ends thereof to provide a chamber 14 to receive the moisture absorbing element 15.

The upper edges of the casings 9 are supported in operative position by means of brackets 16 carried by the band 1 and here shown secured thereto by the same bolts which secure the brackets 8. Extending laterally and downwardly from the upper

edges of the casings 9 are light-guards or shields 17 which prevent the sun from shining on the mirrors and interfering with their reflection of the objects in the street 5 over which they are disposed.

These mirrors 11 are so positioned and focused that when the device is positioned centrally over intersecting streets as shown in Fig. 1, they will reflect objects in the 10 cross streets some distance beyond the intersection of said streets, as is shown clearly in Fig. 1, the frame being positioned with the points thereof in alinement with the longitudinal center of the streets and the 15 focus points of said mirrors being indicated at F.

From the above description it will be obvious that the driver of a vehicle or other person on reaching the intersecting streets 20 at the point over which this reflector is disposed, may by glancing into one of the mirrors thereof, observe any approaching vehicle which is still out of sight to the naked eye and hence give him ample time 25 to avoid collision therewith.

By the use of this device many accidents at street crossings may be avoided and the device may be supported either over the center of the street crossings or at each of 30 the four corners thereof.

The mirrors constituting the reflecting elements of this device may be either concave, convex or rectilinear to obtain the proper focus.

35 From the foregoing description, taken in connection with the accompanying drawing, the advantages of the construction and of the method of operation will be readily apparent to those skilled in the art to 40 which the invention appertains and while I have described the principle of operation of the invention together with the device which I now consider to be the best embodiment thereof, I desire to have it understood 45 that the device shown is merely illustrative and that such changes may be made as are within the scope of the claimed invention.

I claim:

50 1. A reflector of the class described comprising a spider having an attaching collar, a substantially rectangular band supported by said collar, brackets depending from said band and having their lower 55 ends converging and provided with hooks,

mirror containing casings supported at their lower edges in said hooks, and other brackets carried by said band and engaging the upper edges of said casings.

2. A reflector of the class described comprising a spider having an attaching collar, a substantially rectangular band supported by said collar, brackets depending from said band and having their lower ends converging and provided with hooks, mirror containing casings supported at their lower edges in said hooks, other brackets carried by said band and engaging the upper edges of said casings, and light guards or shields 65 extending laterally and downwardly from the upper edges of the casings.

3. A reflector of the class described comprising a spider having arms with a collar connecting their inner ends, the free ends of said arms being bent laterally outward and upward to form hangers, a substantially rectangular band supported by said hangers, brackets depending from said band and having their lower ends bent outwardly and upwardly to form hooks, said 75 brackets converging toward their lower ends, securing clips carried by the free ends of said spider arms above the hooks and adapted to cooperate to engage the upper edge of said band for clamping and holding it in engagement with said hooks, mirror containing casings supported at their lower edges in the hooks of said brackets, and means carried by said band for engaging the upper edges of said casings.

4. In a device of the class described, the combination of a supporting frame, of a rectangular frame carried thereby, each of its side walls having its ends converging toward the lower edge thereof and formed 95 of a plate having pockets on its outer face at its upper and lower edges, said pockets opening toward each other, a mirror arranged on the outer face of said plate with its upper and lower edges disposed in said 100 pockets, said plate being offset outwardly adjacent said pockets to form a chamber at the back of said mirror, and a moisture absorber disposed in said chamber.

In testimony whereof I affix my signature 105 in presence of two witnesses.

CHARLES C. MASON.
